UNITED STATES PATENT OFFICE.

FRANKLIN HARDINGE, OF CHICAGO, ILLINOIS, ASSIGNOR TO HARDINGE BROTHERS, INC., OF CHICAGO, ILLINOIS, A CORPORATION OF ILLINOIS.

OIL BURNER.

Application filed May 16, 1921. Serial No. 470,211.

To all whom it may concern:

Be it known that I, FRANKLIN HARDINGE, a citizen of the United States, and resident of Chicago, in the county of Cook and State 5 of Illinois, have invented a certain new and useful Improvement in Oil Burners, of which the following is a full, clear, concise, and exact description, reference being had to the accompanying drawings, forming a 10 part of this specification.

My invention relates to improvements in oil burners and is particularly concerned with improvements in those types of oil burners which are designed to burn gas oil, 15 fuel oil and other petroleum distillates and residuums. More particularly my invention is concerned with improvements in that type of oil burner in which a rotary atomizing nozzle is used for atomizing the fuel 20 which is subsequently mixed with air to form a combustible mixture.

In my co-pending application Serial No. 389,794 I have disclosed an oil burner comprising a rotary atomizing nozzle which is 25 mounted upon the upper end of a cup which serves as a centrifugal separator for separating the impurities in such a manner as to prevent the nozzle from becoming clogged and covered with carbonized oil.

30 My present invention contemplates certain improvements in the type of burner disclosed in my aforesaid application, and among its objects are:

First: To provide a burner comprising 35 means for supplying the oil to the atomizing nozzle of such a character and construction as to permit very small quantities of oil to be continuously fed to the nozzle.

Second: To provide means for feeding 40 the oil to the atomizing nozzle so constructed as to separate air from the oil before the oil is delivered to the atomizing nozzle, so as to prevent the flame from being extinguished by the bubbles of air in the oil supply means.

Third: To provide means for preventing 45 the oil, and particularly oil which has a percentage of water mixed therewith, from assuming or tending to assume a spheroidal state in passing from the supply means to the atomizing nozzle.

Fourth: In an oil burner of the character 50 described to provide improved means for preventing the fuel oil from becoming mixed with the lubricating oil; and,

Fifth: To provide a new type of agitator for preventing the cup forming the centrifugal separator from becoming clogged up with impurities deposited from the fuel oil.

Other objects will appear as this description progresses, reference being had to the accompanying drawings, wherein—

Figure 1 is a central vertical section taken through an oil burner embodying my improvements, portions of the apparatus being 65 shown in elevation;

Figure 2 is a side elevation showing certain features of construction of my improved means for supplying lubricant to the burner and my improved agitator;

Figure 3 is an enlarged sectional detail; and

Figure 4 is a transverse section taken substantially on line 4—4 of Figure 2.

Throughout the several views similar reference characters will be used to refer to similar parts.

In my co-pending application above referred to I have disclosed an oil burner comprising a hollow shaft 5 which is rotatably 80 mounted in suitable bearings 6, one only of which is shown, and carrying at its upper end a cup comprising an inner cylindrical wall 7 and the outer cylindrical wall 8, which are spaced apart to provide an annular space 9 for holding the fuel oil. An outwardly flaring atomizing nozzle 10 is provided at its lower end with a flange 11 the edge of which is screwthreaded as shown at 85 12, to provide means for detachably securing it to the upper edge of the cup. The diameter of the bore of the atomizing nozzle is smaller than the diameter of the cup, thereby providing an annular ring-shaped space 90 between the top and bottom of the cup for holding the oil while it is being subjected to centrifugal force. The stand-pipe 13 extends through the hollow shaft 5 and projects upwardly through the inner cylindrical wall 7 of the cup and into the bore of the 100 atomizing nozzle 10.

The construction thus far described is similar to that described in my co-pending application above referred to, wherein I have also disclosed means for rapidly rotating the shaft 5 so as to cause the oil to be thrown from the knife edge 14 of the atomizing nozzle in an exceedingly fine spray. The spray thus formed is mixed with air discharged from the fan plates 15 which are 110

secured to the outer side of the atomizing nozzle adjacent the knife edge 14. The oil spray and air thus mixed will form a combustible mixture which can be readily ignited and which burns with a very intense white flame, practically free from smoke and odor.

In my co-pending application, above referred to, I have illustrated the stand-pipe 10 as being provided with comparatively small round openings for discharging its contents into the cup. Experiments with the burner thus constructed have demonstrated that it is difficult to supply a comparatively small 15 amount of oil to the burner, such for instance as one-half gallon, or less, of oil per hour, and maintain a continuous fire. With a burner thus constructed I have found that where a half gallon of oil or less per hour 20 is being consumed the flame is quite often completely extinguished. After considerable experimentation and investigation, I have discovered that this tendency of the flame to become extinguished is due, first, 25 to the air held in solution in the oil, which tends to accumulate in the stand-pipe, and when it finally passes through the orifices in the stand-pipe it momentarily discontinues the supply of oil to the atomizer and thus 30 causes the flame to become extinguished.

Secondly, some oils contain a considerable percentage of water, which tends to cause the oil to assume a more or less spheroidal state as it issues from the round orifices, in 35 place of flowing freely as it should, and in this manner prevents a continuous supply of fuel to the burner. To prevent the above mentioned actions, I have provided the upper end of the stand-pipe with longitudinally extending parallel slots 16, the discharge capacity of which is considerably greater than the maximum capacity of the oil burner so that under no condition of operation will these slots be completely filled 40 with oil. In this manner I provide a space above the surface of the column of oil in the stand-pipe 13, wherein the air in the oil can be readily disengaged and escape through the open upper ends of the slots 16.

50 I have discovered, with the slots more or less elongated, there is not the same tendency for the oil to assume a globular form where it contains a considerable amount of water as it is where the openings in the 55 stand-pipe are circular in form.

In my aforesaid co-pending application, I have disclosed a cap similar in some respects to the cap 17 shown herein which surrounds the stand-pipe and encloses the cylindrical inner wall 17 of the cup. In my prior application the oil is evenly distributed over this cap through a plurality of openings. When a small amount of oil, such as referred to above, is discharged over such a cap from 65 a plurality of different points the film of oil

formed upon the flange of the cap is so exceedingly thin that it is easily disrupted and the flame may thus become extinguished. In my present construction I have provided means for more or less localizing the flow of oil over the surface of the cap and in this manner I produce a more restricted but thicker film of oil which does not so easily become disrupted. For this purpose I place the lower edges 18, 19, 20 and 21 of the different slots in different planes, so that when only a very small quantity of oil is being fed to the nozzle it will all flow over the edge 18. If the quantity of oil is then increased, a portion of it will flow over the edge 19, and if still further increased an additional quantity will flow over the edge 20, and in the same manner if the quantity is still further increased, a portion of it will flow over the edge 21. The cap 17 is provided with a plurality of grooves 22 which register with the slot 16 and the walls of which serve to confine the oil flowing therethrough to a restricted portion of the outer surface of the flange of the cap 17 instead of permitting it to spread all over the outer surface, and thus become so exceedingly thin that it is likely to be disrupted.

During operation the air within the cap 17, and, perhaps, that in the stand-pipe becomes more or less heated and rarefied and when the burner is subsequently stopped and the oil and water in the cup drop down under the influence of gravity and fill the lower portion of the cup, there is a tendency for this oil and water to be drawn over into the space between the inner wall 7 and the stand-pipe and to run down between the stand-pipe and the hollow shaft 5, and thus contaminate the lubricating oil which, as described in my co-pending application above referred to, is held in a well at the lower end of the hollow shaft. To prevent such an occurrence, I vent the interior of the cap 17 to atmosphere by forming a groove 18 in the outer surface of the stand-pipe 5 which extends from a point above the top of the cap 17 to a point inside of the cap 17, thus venting the interior of the cap to atmosphere.

For agitating the contents of the cup to prevent the impurities from becoming permanently deposited in the cup, I provide an agitator comprising a ring 23 which surrounds the cylindrical wall 7 immediately beneath the lower edge of the cap 17 and which is provided with a plurality of outwardly extending agitator arms 24, the horizontal portions of which are preferably tilted as shown in Figure 1, to provide a reaction surface which tends to lift them and the attached ring when the cup is rotated. The ring 20 is provided with a pair of upstanding lugs 25, the leading faces of which are beveled as shown at 26, and engage the lugs 27 extending inwardly from the lower edge 130

of the cap 17. In action when the cup is rotated the fluid contents thereof engage the lower sides of the horizontal portions of the agitator arms and react against the same 5 tending to cause these arms to rotate with the contents of the cup. This pressure causes the beveled edges 26 of the lugs 25 to ride upwardly on the lugs 27, thereby bringing the ring 23 into close contact with the 10 lower edge of the cap 17, so that there will be no tendency for the oil to form in drops before flowing on to the ring 23. The ring 23 may have a plurality of openings 23' formed therein for conducting the oil from 15 the lower edge of the cap 17 to the annular ledge 7' which discharges the oil into the cup. I found, however, that the openings 23' are not essential to the proper operation of my burner. It is quite important, however, that the space between the ring 23 and the lower edge of the cap 17 should not be as 20 large as the diameter of a drop of the oil which is being burned. If this precaution is exercised there will be no tendency for the oil to form drops and thus tend to interrupt the supply of oil to the atomizing nozzle.

There is a tendency for the agitator to form a slight spray which tends to settle upon the surface of the bore of the atomizing nozzle adjacent the lower end of the bore and to become carbonized there. To prevent this I have slightly counter-bored the lower end of the bore of the atomizing nozzle, as shown at 27 so as to make a film of oil at 35 this point sufficiently thick to prevent the spray from adhering to the nozzle wall.

I have also provided a ring or disk 28 which surrounds the stand-pipe immediately above the top of the cap 17 and which is 40 provided with grooves 29 which register with the slots 16 formed in the stand-pipe. These slots will carry off any abnormal supply of oil which may be forced through the stand-pipe, and that portion of the ring 45 which overlies the groove 13' will prevent any of such abnormal supply from finding its way through the groove 18 to the space between the stand-pipe and the rotary shaft 5. The disk 28 also tends to prevent the 50 spray formed by the agitator from finding its way to the upper portion of the atomizing nozzle.

While I have described the details of construction of the preferred embodiment 55 of my invention, it is to be clearly understood that my invention is not to be limited to these details but is capable of other adaptations and modifications within the scope of the appended claims.

Having thus described my invention what I claim is:

1. An oil burner comprising a rotary hollow shaft, a cup mounted on the upper end of said shaft, said cup having inner and outer 65 cylindrical walls spaced apart to provide an

oil receptacle, an upwardly flaring atomizing nozzle mounted on the upper end of said cup, the bore of said nozzle where it opens into said cup being smaller in diameter than said cup and being counter-bored, a stand-pipe 70 projecting through said hollow shaft and the inner cylindrical wall of said cup, the upper end of said stand-pipe being provided with a plurality of longitudinally elongated slots, the bottom edges of said slots lying in different planes, a cap surrounding said stand-pipe and enclosing said inner cylindrical wall of said cup, the top of said cup having grooves formed therein for conducting the oil from the slots in said stand-pipe to the outer wall of said cap, an annular disk 75 surrounding said stand-pipe above said cap and having radial grooves formed therein registering with the upper end of the slots in said stand-pipe, said stand-pipe having a groove cut in the surface thereof extending from a point within said cap to a point above said annular disk, a ring surrounding said stand-pipe below said cap, an agitator arm extending outwardly from said ring, and means within said cap for holding said ring stationary.

2. An oil burner comprising a rotary hollow shaft, a cup mounted on the upper end of said shaft, said cup having inner and outer cylindrical walls spaced apart to provide an oil receptacle, an outwardly flaring atomizing nozzle mounted on the upper end of said cup, a stand-pipe projecting through said hollow shaft and the inner cylindrical wall of said cup, the upper end of said stand-pipe being provided with a plurality of longitudinally elongated slots, the bottom edges of said slots lying in different planes, a cap surrounding said stand-pipe and enclosing said inner cylindrical wall of said cup, the top of said cup having grooves formed therein for conducting the oil from the slots in said stand-pipe to the outer wall of said cap, a ring surrounding said stand-pipe below said cap, an agitator arm extending outwardly from said ring, and means within said cap for holding said ring stationary.

3. An oil burner comprising a rotary hollow shaft, a cup mounted on the upper end of said shaft, said cup having inner and outer cylindrical walls spaced apart to provide an oil receptacle, an upwardly flaring atomizing nozzle mounted on the upper end of said cup, a stand-pipe projecting through said hollow shaft and the inner cylindrical wall of said cup, the upper end of said stand-pipe being provided with a plurality of longitudinal elongated slots, the bottom edges of said slots lying in different planes, a cap surrounding said stand-pipe and enclosing said inner cylindrical wall of said cup, and the top of said cup having grooves formed therein for conducting the oil from the 115 120 125 130

- slots in said stand-pipe to the outer wall of said cap.
4. An oil burner comprising a rotary hollow shaft, a cup mounted on the upper end 5 of said shaft, said cup having inner and outer cylindrical walls spaced apart to provide an oil receptacle, an outwardly flaring atomizing nozzle mounted on the upper end of said cup, a stand-pipe projecting through 10 said hollow shaft and the inner cylindrical wall of said cup, the upper end of said stand-pipe being provided with a plurality of longitudinally elongated slots, the bottom edges of said slots lying in different planes, 15 and a cap surrounding said stand-pipe and enclosing said inner cylindrical wall of said cup.
5. An oil burner comprising a rotary hollow shaft, a cup mounted on the upper end 20 of said shaft, said cup having inner and outer cylindrical walls spaced apart to provide an oil receptacle, an outwardly flaring atomizing nozzle mounted on the upper end of said cup, a stand-pipe projecting through 25 said hollow shaft and the inner cylindrical wall of said cup, and the upper end of said stand-pipe being provided with a plurality of longitudinally elongated slots.
- 30 6. An oil burner comprising a rotary hollow shaft, a cup mounted on the upper end of said shaft, an upwardly flaring atomizing nozzle mounted on the upper end of said cup, a stand-pipe projecting through said 35 hollow shaft and into the cup, and the upper end of said stand-pipe being provided with a longitudinally elongated slot.
7. An oil burner comprising a rotary atomizing nozzle and, a stand-pipe projecting 40 through the center of said nozzle and having a longitudinally elongated slot for supplying oil to said atomizing nozzle.
8. An oil burner comprising an atomizing nozzle, and a stand-pipe having a longitudinally elongated slot for discharging oil onto 45 said atomizing nozzle.
9. The combination with an atomizing nozzle of a conduit for supplying oil to said nozzle, having a vertically disposed horizontally discharging aperture larger than required to discharge the maximum quantity 50 of oil to be burned, for permitting air to separate from the oil and escape and for preventing the oil from tending to assume 55 the spheroidal state.
10. An oil burner comprising a rotary atomizing nozzle, a distributing device for 60 supplying oil to said nozzle, and means for supplying oil to said distributing device over an area varying with the quantity of oil being fed to said nozzle.

11. An oil burner comprising a cup having inner and outer cylindrical walls, means for rotating said cup, an upwardly flaring atomizing nozzle secured to the upper end of 65 said cup and receiving fuel therefrom, a stand-pipe projecting through said inner cylindrical wall and having an opening near its upper end for discharging oil into said cup, a cap surrounding said stand-pipe and enclosing said inner wall, a ring surrounding 70 said stand-pipe, an agitator projecting from said ring toward the wall of said cup, and means for preventing said ring from rotating with said cup.

12. An oil burner comprising a cup having inner and outer cylindrical walls, means for rotating said cup, an atomizing nozzle secured to the upper end of said cup and receiving fuel therefrom, a stand-pipe projecting through said inner cylindrical wall and having an opening near its upper end for discharging oil into said cup, a cap surrounding said stand-pipe and enclosing said 75 inner wall, and means for preventing the interior of said cup from rotating with said cup.

13. An oil burner comprising a hollow shaft, an atomizing nozzle secured to the upper end of said shaft, a stand-pipe projecting through said shaft and the bottom 80 of said nozzle for supplying oil to said nozzle, a cap surrounding the upper end of said standpipe and the upper open end of said hollow shaft, and means above the lower edge of said cap for venting the interior of 85 said cap to atmosphere.

14. An oil burner comprising a cup, an atomizing nozzle secured to the upper end of said cup, and receiving oil therefrom, the bore of said atomizing nozzle where it communicates with said cup being of less diameter than the diameter of said cup and being counter-bored, means for agitating the oil in said cup, and a disk mounted in the counterbored portion of said atomizing nozzle, the said disk having a diameter slightly less than said counter-bore.

15. An oil burner comprising a cup, an atomizing nozzle secured to the upper end 100 of said cup, and receiving oil therefrom, the bore of said atomizing nozzle where it communicates with said cup being of less diameter than the diameter of said cup and being counterbored, and means for agitating the oil in said cup.

In witness whereof, I hereunto subscribe my name this 11th day of May, 1921.

FRANKLIN HARDINGE.
